UNITED STATES PATENT OFFICE.

ANDREW H. HAYNES, OF SISSONVILLE, WEST VIRGINIA.

MAIL-BOX.

1,200,880.

Specification of Letters Patent.

Patented Oct. 10, 1916.

Application filed September 17, 1915. Serial No. 51,227.

To all whom it may concern:

Be it known that I, ANDREW H. HAYNES, a citizen of the United States, residing at Sissonville, in the county of Kanawha and State of West Virginia, have invented certain new and useful Improvements in Mail-Boxes, of which the following is a specification.

The invention relates to mail boxes, and 10 more particularly to the class of rural mail receptacles.

The primary object of the invention is the provision of a mail box or receptacle of this character, wherein it is formed from a single 15 piece of material, preferably sheet metal, and affords independent compartments for the deposit of small mail matter in one of the same, while the other compartment is adapted to receive larger mail matter.

20 Another object of the invention is the provision of a mail box or receptacle, of this character, wherein the construction is novel in form, so that different classes of mail matter can be conveniently segregated, to assure 25 the handling of the same with despatch.

A further object of the invention is the provision of a mail box or receptacle, of this character which is extremely simple in construction, thoroughly reliable and efficient in 30 its purpose, strong, durable, weather-proof, and inexpensive in manufacture.

With these and other objects in view the invention consists in the features of construction, combination and arrangement of parts 35 as will be hereinafter more fully described in detail, illustrated in the accompanying drawing, and pointed out in the claim hereunto appended.

In the accompanying drawing: Figure 1, 40 is a plan view of a blank from which the mail box or receptacle constructed in accordance with the invention is made. Fig. 2, is a front elevation of the mail box or receptacle. Fig. 3, is a vertical longitudinal sec- 45 tional elevation. Fig. 4, is a rear elevation.

Similar reference characters indicate corresponding parts throughout the several views in the drawing.

Referring to the drawing in detail, the mail box or receptacle comprises a blank A, 50 preferably metal, which is cut to form the front wall 5, rear wall 6, side walls 7, bottom 8, sloping roof sections 9, and a rear upwardly tapering extension 10, which constitute the body of the said box or receptacle. 55

The body of the mail box or receptacle is formed into upper and lower compartments 11 and 12, respectively, through the medium of a horizontal partition 13, which is cut and bent from the blank A. The free edges of 60 the blank A, are joined with each other by solder, although the same may be overlapped and riveted if desired. Provided in the front wall 5, is an elongated slot 14, through which is inserted first class mail matter for the introduction thereof into the lower compartment 12, in the body of the box or receptacle. The upper compartment 11, is open at its front to permit the placing of parcel post matter therein, although if found desirable 65 a door or other closure may be provided at the front of this compartment for closing the same, while formed in the rear wall 6, is a suitable doorway, which is adapted to be closed through the medium of a swinging 70 door 15, having a lock, and this doorway permits the removal of the first class mail matter by the user of the box or receptacle.

From the foregoing it is thought that the construction and manner of use of the box 80 or receptacle will be clearly understood and therefore a more extended explanation has been omitted.

What is claimed is:—

A mail box, comprising a blank of mate- 85 rial cut and folded to provide a box-like body, including top, bottom, sides and ends, one end being extended above the top and having a tapered portion, the opposite sides being extended and bent toward each other 90 to meet the tapered portion and adapted to be united thereto and to each other to provide a chamber above the body, said chamber being open throughout the front thereof.

In testimony whereof I affix my signature. 95
ANDREW H. HAYNES.
